UNITED STATES PATENT OFFICE.

CHRISTIAN GÖRLITZ, OF ALTONA-OTTENSEN, GERMANY.

JOINER'S BENCH.

1,205,884.

Specification of Letters Patent. Patented Nov. 21, 1916.

Application filed October 27, 1914. Serial No. 868,866.

To all whom it may concern:

Be it known that I, CHRISTIAN GÖRLITZ, a subject of the German Emperor, residing at Altona-Ottensen, Germany, have invented 5 a new and useful Joiner's Bench, of which the following is a specification.

The invention relates to a joiner's bench which can be mounted upon tables or the like.

10 The novelty of this bench consists of the two cramps or clamping parts of such a new construction that these parts can be used upon the well known table-bench-board for all works or purposes of the joiner. Essentially 15 these parts can be used as a horizontal cramp or clamping device which hitherto was not possible by only using the two clamping parts of the known joiners' benches for tables.

20 In the accompanying drawing a form of construction of the invention is represented.

Figure 1 shows a perspective view on a reduced scale of the bench board made of wood which can be mounted upon a table. 25 Figs. 2 and 3 show perspective views of the two cramps or clamping parts essentially already well known but the construction of which is partly a new one. Fig. 4 shows a 30 perspective view of a third part which can be used for greater security of the clamping device. Fig. 5 represents a perspective view of a part of the joiner's bench with the two above mentioned clamping parts mounted to act as a horizontal clamping device with 35 addition of the third (security) part.

The wooden board *a* is provided with the known vertical round holes *a*¹ and horizontal holes *a*². Furthermore the board has a horizontal metal-plate *a*³ with a vertical 40 hole *a*⁴ which is not wholly round but provided with plane inner surfaces *a*⁵. The front side of the board *a* has furthermore two vertical metal plates *a*⁶ with openings *a*⁷ which have plane side-walls *a*⁸.

45 All holes or openings of the board *a* have the same diameter with the exception of the holes in the plates *a*³ and *a*⁶. A little vertical hole *a*⁹ crosses the horizontal hole *a*⁷. The clamping bolt *b* (Fig. 2) has a round 50 cross-section of such a diameter as to fit into any of the holes *a*¹ or *a*². Thereby the head *b*¹ of the bolt touches the top surface of the board *a*. The under half of this clamping bolt has planes *b*² so that if the 55 bolt is mounted in any of the holes *a*⁴ or *a*⁷ in the plates *a*³ or *a*⁶, respectively, the upper

half of the bolt protrudes as shown in Fig. 5 above the board *a*. Furthermore the two opposite planes *b*² prohibit the turning of the bolt. Through the lower end is a hole *b*³. The head *b*¹ of the bolt has a ribbed plane *b*⁶ and a bore *b*⁴ of not wholly round cross-section with two plane inner surfaces *b*⁵. The clamping screw spindle *c* has a bolt *d* of the same diameter as the holes *a*¹ but 60 which is furthermore provided with planes *d*¹ opposite each other. The spindle *c* has a turnable head *c*¹ ribbed upon its outer surface *c*². The other end of the spindle is provided with a handle or lever *c*³. The 65 spindle can be screwed into the nut *d*² forming the head of bolt *d*. The bolt *e* Fig. 4, has an under part of round cross-section *e*¹ fitting into any of the holes or bores *a*¹ (but not into the bores *a*⁴ or *a*⁷). At the upper 70 end is a ring *e*².

The two clamping parts *b* and *d* can be inserted in any of the openings *a*¹ and *a*² but in order to construct the horizontal cramp according to Fig. 5 the bolt *d* is inserted 75 into the bore *b*⁴ and the under end of bolt *b* is inserted into the opening *a*⁷ of plate *a*⁶ and pin *f* is inserted into the corresponding holes *a*⁹ and *b*³. Now the two parts *b* and *d* are ready as horizontal clamping devices of the kind shown in Fig. 5. In order 80 to increase the stability of this device the bolt *e* can be used as shown in Fig. 5. For this purpose the under end *e*¹ is inserted into one of the holes *a*². The foot *e*³ then 85 stands upon the side surface of the board *a* and the ring *e*² surrounds the free end of bolt *d* thus serving as an abutment. Hitherto the bolts *b* and *d* could not be used as such a horizontal clamping device. In order 90 to enable this new use, the bolt *b* is now provided with the hole *b*⁴ with two planes *b*⁵ and with two planes *b*², the bore *b*³ and the pin *f*. The table board *a* is for the same 95 purpose provided with the plate *a*⁶ with opening *a*⁷ with planes *a*⁸. Furthermore the not wholly round hole *b*⁷ and the correspondingly formed shaft with planes *d*¹ of bolt *d* are novel.

I claim:

A joiner's bench for use upon tables or the like comprising in combination a wooden board with a plurality of horizontal and vertical holes and having at its ends plates having not wholly round openings 100 with plane sides respectively and a hole crossing one of the first mentioned openings, 110

a bolt having at its lower end planes fitting into one of said openings and a not wholly round hole arranged parallel to said latter planes, a spindle with cramping foot and handle and a bolt having planes fitting the planes of one of the first mentioned openings, a pin adapted to engage with one of the holes first mentioned and that in the

bolt, a bolt adapted to serve for an abutment for the free end of the first mentioned bolt and having a foot fitting into any horizontal hole.

CHRISTIAN GÖRLITZ.
